UNITED STATES PATENT OFFICE

SAMUEL N. HOPE, OF WAUWATOSA, WISCONSIN, ASSIGNOR TO DUDLEY LOCK CORPORATION, OF CHICAGO, ILLINOIS, A CORPORATION OF ILLINOIS

COMBINATION LOCK

Application filed March 15, 1930. Serial No. 436,007.

This invention relates to certain novel improvements in locks, and more particularly to locks of the permutation or keyless type, especially constructed for use in connection with wall safes, locker doors, drawers, and various other forms of closures. One of the objects of this invention is to provide in a lock of this character, a generally improved construction which is simple, durable, positive in operation, and capable of being economically manufactured. Another object is to provide in a lock of the character mentioned a relatively simple construction which permits quick and easy alteration of the combination in the "field". A further object is to provide an improved lock construction in which a large number of different combinations may be attained in assembly when using a given set and arrangement of tumbler elements. A still further object is to produce an improved lock construction wherein the tumbler elements are supported in spaced relation to and substantially independently of the lock bolt actuating spindle. And a still further object of this invention resides in an improved method for conveniently ascertaining the combination of a lock in the "field". The invention consists in certain features and elements of construction in combination, as herein shown and described, and as indicated by the claims.

In the drawings:—

Figure 1 is a face view in elevation of a lock embodying the present invention, shown as applied to a panel type of closure member.

Figure 2 is an edge elevation.

Figure 3 is an enlarged vertical axial section, taken substantially as indicated at the line, 3—3, on Figure 1.

Figure 4 is a rear view with the back of the casing removed, showing the locking mechanism in adjusted position ready to permit retraction of the locking bolt.

Figure 5 is a disassembled perspective view of parts of the lock, showing the front of the

casing, together with the dial plate and escutcheon plate.

Figure 6 is a disassembled perspective view of the casing proper, looking into the interior of the main part thereof.

Figure 7 is a perspective, axial disassembly of the rotatable elements of the locking mechanism.

Figure 8 is an enlarged face view of a part of the lock showing the dial, together with the tumbler setting knob and lock bolt actuating knob.

The present invention represents certain novel refinements in lock construction of the general type disclosed in my co-pending joint application with John J. Neitz, bearing filing date February 27, 1929 and Serial No. 343,034.

Referring now to the drawings, the lock is shown for purpose of illustration, affixed to the inner side of a panel type closure member, 1, adjacent its lateral edge; it being understood, however, that the lock may be secured either to the movable closure member or the co-operating fixed member for closures, such as lockers, vaults, drawers, etc. The lock proper consists of a casing having a rectangular cup-shaped body part, 2, and a back cover plate, 3, secured thereto in any suitable manner, and as herein shown, by engagement of the tangs, 2^a, on the body casing part, 2, in the apertures, 3^a, of the back cover plate. Secured to the front of the casing part, 2, is a plate, 4, having a pair of oppositely extending ears, 5, for securing of the lock casing to inner side of the panel, 1, by means of button head bolts, 6, and the nuts, 7, as may be seen in Figure 3; the bolts being arranged so that their round heads are exposed on the outer side of the panel member to preclude unauthorized removal of the lock from its mounting when the closure member is in locked position. If desired, this front plate member, 4, may be formed as an integral part of the casing, 2, and as seen in the drawings,

said front plate is provided with a laterally projecting annular sleeve, 8, substantially central with respect to the cup-shaped part of the casing, 2; said sleeve projecting through and beyond the front side of the panel, 1, and serving as a journal bearing for a tumbler actuating knob, indicated at 10.

This tumbler actuating knob which is of substantially cylindrical form, is provided with an annular flange, 11, adapted to be seated against the inner side of the front plate, 4, for preventing said knob from being withdrawn from the casing in an outward direction, the front part of the cup-shaped casing, 2, being provided with an opening to accommodate said annular flange, 11, of the tumbler actuating knob, (as seen in Figure 3). The portion of the tumbler actuating knob which extends beyond the panel, 1, is provided with a series of parallel longitudinally extending peripheral grooves, 12, preferably arranged in pairs in diametrically opposite relation for engagement with a pair of co-operating, inwardly projecting diametrically opposite lugs or tongues, 13, of an annular graduated dial plate, 14, which is arranged concentrically on said knob. As shown in the drawings, one of the lugs, 13, is located in line with the zero graduation of the dial, and it may be understood that actually this one lug will suffice, but I preferably employ two lugs for a balanced construction. To give the knob a more uniform appearance the peripheral surface thereof intermediate the grooves, 12, is preferably formed with grooves of lesser depth, giving the knob as a whole a somewhat knurled effect. The purpose of the plurality of sets of main grooves, 12, in the tumbler-actuating knob is to permit changing of the combination of the lock in the "field", as will hereinafter be fully explained. For convenience in assembly of the lock it is preferable to have some index of a standard arrangement of assembly of the knob with respect to the dial, and accordingly I designate one of the grooves, 12, as a main groove, 12^a, for the initial assembly "set-up" by forming the shallow grooves on the opposite sides thereof of shorter length than the other grooves, as indicated at 15, so that in assembling the lock for initial set-up, the groove, 12^a, may be selected at a glance for engagement with the lug, 13, at the zero point of the dial.

The dial plate, 14, is formed at the rear side thereof with an annular recess, 17, dimensioned for journaling on the outer periphery of the casing sleeve, 8, as may be seen in Figure 3, so that the dial will be maintained concentrically of the tumbler setting knob and supported substantially independently thereof, and the only engagement of said parts being by said tongue-and-groove connection by means of which the dial may be rotated with the knob.

Force fitted on the sleeve, 8, rearward of the dial, 14, and abutting against the front side of the front plate, 4, is an annular cup-shaped member, 18, having an up-turned annular peripheral flange, 19, of slightly larger diameter than the dial. An escutcheon plate, 20, is secured to the front side of the panel member, 1, by the bolts, 6, and is formed with an annular offset portion, 21, dimensioned to fit around the outer surface of the peripheral flange, 19, and overlapping the marginal edge of the dial face, the upstanding flange, 19, thus insuring proper clearance for free movement of the dial under the escutcheon plate. Thus the dial is merely maintained captive by the escutcheon plate, and retained against lateral axial movement in an outward direction, while the end of the sleeve, 8, prevents axial movement of said dial in the opposite direction. The face of the dial may be graduated in any suitable form for convenience in setting the tumbler mechanism in combination; since the dial is rotatable with the tumbler setting knob, it is necessary to provide some initial index or starting point, and, accordingly, the escutcheon plate is formed with an index element in the nature of a depression, 22, with which the graduations of the dial may be registered.

It will now be apparent that the combination of the lock may be quickly and easily changed in the "field" by merely loosening the bolts, 6, permitting the removal of the escutcheon plate and dial, so that the lugs, 13, may be shifted angularly relative to the knob, 10, for engagement with a different set of grooves, 12, thereby altering the combination. As illustrated in the drawings, it will be noted that the tumbler setting knob is provided with eight main longitudinal grooves, 12, which are adapted to be selectively registered with the lug or tongue, 13, which corresponds to the zero graduation of the dial, thus affording eight selective positions of adjustment of the knob relative to the dial. Hence, merely shifting the dial the angular amount for registration with the next successive main groove, 12, will alter the combination by five points on a dial (because it has forty graduations) which numerical amount may be added to or subtracted respectively from the previous combination numbers for ascertaining the new combination of the lock. This feature is of especial advantage where it is necessary to alter the combinations of the lock at various intervals, such as when it is used on lockers, drawers, etc., of institutions, such as schools, clubs, etc., where the locker and drawers are changed and re-assigned to different individuals at various times. Disposed concentrically of the tumbler-actuating knob is a spindle, 25, having its inner end counter-bored at 26 and journaled on a stud, 27, rigidly secured on the inside of the casing back

plate, 3, as seen at Figure 3, and having a portion adjacent said end journaled in the annular sleeve, 28, which is secured to said tumbler-actuating knob, 10, and extends a substantial portion of the depth of the casing. The outer end of the spindle is provided with an operating knob, 29, journaled in the outer end of the tumbler actuating knob, 10. Rigidly secured to the inner end 5 of the spindle is an operating arm, 31, engageable in a groove, 32, of a laterally shiftable lock bolt, 33, loosely mounted in the casing for shifting said bolt into and out of locking position.

10 Loosely mounted on said sleeve, 28, of the tumbler actuating knob are a plurality of axially spaced tumblers, 35, having inter-engaging features in the nature of laterally projecting lugs, 36, by means of which said tumblers may rotatably adjust each other into a predetermined arrangement. These tumblers are spaced apart to insure proper driving engagement of their lugs by intermediate horseshoe shaped spacer members, 37, which are anchored against rotation or shifting in transaxial direction, on a pair of pins, 38, secured to the interior of the casing, 2. These spacing elements thus serve to prevent transmission of rotary motion from one 20 of the tumbler elements to the other. The transaxial inner face of the flange 11, of the tumbler actuating knob, 10, is provided with a plurality of angularly spaced apertures, 39, in any one of which may be engaged the driving lug, 36, of the first or master tumbler by virtue of which said knob may transmit rotary motion to all the tumblers of the series for setting them in proper combination. The tumblers are each provided with 25 a pair of notches, 35^a, opening at the periphery and arranged for receiving the co-operating projections, 33^a, of the lock bolt, when the notches of all the tumblers are aligned by the setting of the tumblers in a predetermined combination to permit free shifting of the lock bolt by rotation of the spindle, into and out of locking position.

30 Interposed between the last tumbler of the series and the lock bolt operating arm, 31, is a convex spring member, 40, herein shown as of spider formation with a plurality of radially extending tangs, 41, connected together at central portion, 42, which is of relatively small diameter, so that the yielding pressure may be transmitted from the operating member, 31, to the last tumbler of the series with the minimum possibility of imparting rotary motion from said member, 31, to the tumblers. For the purpose of illustration it may be seen in Figure 3 that this convex spring element, 40, is arranged with the radial tangs, 41, engaging the operating member, 31, and with the relatively small central area, 42, transmitting spring pressure through the medium of an interposed

washer, 43, to the last tumbler of the series, thus tending to maintain the tumblers in proper position for insuring operation and engagement of their lugs for adjusting each other. It will be apparent that the provision of a number of apertures, 39, in the tumbler actuating knob is of especial advantage in that it affords a substantial increase in the possible number of combinations obtainable in the assembly of a lock when employing the same identical arrangement of tumblers, and having the same relative locations of their driving lugs, 36. For example, the tumbler actuating knob is shown provided with eight of these radially spaced apertures which accordingly will provide eight different combinations for the same arrangement of tumbler set up.

35 The tumbler actuating knob beyond the flange, 11, is formed with a cavity, 46, in which is disposed a coil spring, 47, encompassing the shank portion of the spindle, 25, and reacting against a shoulder, 48, of said tumbler actuating knob and the under side of the operating knob of the spindle, thus tending to yieldingly separate said tumbler actuating knob and spindle. It will be manifest that this arrangement of spring, 47, will cause the exertion of a yielding pressure through the arm, 31, to the tumbler mechanism for maintaining said tumblers in operative relation. The pressure transmitted from the operating member, 31, however, is in turn yieldingly transmitted through the medium of the convex spring, 40, to the tumblers for urging and holding them in operative position in positive driving engagement with the tumbler actuating knob at all times.

40 By reason of this arrangement it will be seen that after the tumblers have been set in the combination aligning the notches, 35^a, for receiving the projections, 33^a, of the lock bolt, the spindle may be rotated by the knob, 29, for shifting the lock bolt, 33, into and out of locking position without any possibility of upsetting the tumbler combination. This feature is important in that the lock bolt cannot be inadvertently moved to locking position by rotating the tumbler actuating knob, 10, but positively necessitates first shifting the bolt to locking position by the spindle, so that the projections, 33^a, on the locking bolt, are moved clear out of engagement with the co-operating notches, 35^a, in the tumblers, before the tumbler actuating knob can be rotated for upsetting the tumbler combination.

45 The present invention is also concerned with the provision of an improved method for ascertaining the lock's combination without even demounting the same from the door or other element to which it is secured. Frequently it happens that the combination of a certain lock in use, is inadvertently lost or misquoted, and it is accordingly desirable to

readily ascertain the combination without the necessity of sending the lock back to the manufacturer for disassembly. In order to carry out my improved method, preferably 5 the back plate of the lock is provided with one or more apertures, 51, herein shown as two, with which are adapted to be registered a pair of apertures, 52, in the lock bolt operating arm, 31, when said operating arm is in 10 locking position, as seen in Figure 4. The tumbler actuating knob is first rotated at least two full revolutions in one direction, then a feeler member, having a pair of prongs rigidly connected together, is inserted into the 15 apertures, 51, in the back of the case, through the apertures, 52, in the lock bolt operating arm, until said feelers engage the surface of the last tumbler of the series. The knob, 10, is again rotated in the same direction until 20 the notches, 35^a, of said tumbler are aligned with the apertures in the case and the operating arm, at which time the feeler member is projected laterally therethrough until the ends thereof engage the surface of the intermediate tumbler member. After such adjustment the dial reading is noted and it corresponds to the first number of the combination. The tumbler actuating knob is then 25 rotated one complete revolution in the opposite direction, and then continued rotating in the same direction until the notches, 35^a, in said intermediate tumbler are registered with the notches of the last tumbler and also said apertures, thus permitting the feeler member 30 to be projected through said intermediate tumbler for engaging the surface of the master or first tumbler of the series, and again the dial reading is noted and which corresponds to the second number of the lock's 35 combination. The tumbler operating knob is then rotated in reverse direction until the notches, 35^a, in said master tumbler are aligned with the notches in the other tumblers and said apertures, so as to permit said feeler member to be projected therethrough through 40 said notches, 35^a. After such adjustment the dial reading is again noted and these three numerical readings noted during the successive adjustments of the dial, will correspond to the combination which normally permits opening of the lock. For convenience, the apertures, 51, in the back of the case, and the apertures, 52, in the operating member, are so located as to register with 45 the notches, 35^a, when the same are aligned to permit retraction of the lock bolt. However, it may be readily understood that apertures may be substituted in lieu of said notches and may be located in any other 50 suitable position. It will also be understood that a single aperture in the case, operating arm and in each of the tumblers may also be made to serve the purpose.

I claim:—

65 1. In a permutation lock of the character

described, the combination of a casing, a spindle rotatably mounted in the casing and having a limited range of axial movement, said spindle having an operating knob protruding exteriorly of the casing, a laterally shiftable lock bolt in said casing, a series of spaced tumblers mounted concentrically about the spindle for controlling the movement of the lock bolt, said tumblers having interengaging features for rotatably adjusting one by the other, a separate knob mounted concentrically about the spindle knob, and arranged for adjusting the tumblers in a predetermined combination for releasing the lock bolt, means on the spindle beyond said tumblers, engageable with the bolt, for shifting the same to release position by movement of the spindle after said tumblers have been so adjusted, said spindle and tumbler setting knob being formed to provide a cavity about a portion of the spindle, and a coil spring disposed in the cavity, around said spindle portion and reacting between stop shoulders on the spindle and the tumbler setting knob, tending to separate them in axial direction, thereby causing said lock bolt operating means on the spindle to yieldingly urge the tumblers toward each other, and yieldingly maintain the first tumbler in operative engagement with the tumbler setting knob.

2. In a permutation lock of the character described, the combination of a casing, a spindle rotatably mounted in the casing and having a limited range of axial movement, said spindle having an operating knob protruding exteriorly of the casing, a laterally shiftable lock bolt in said casing, a series of spaced tumblers mounted concentrically about the spindle for controlling the movement of the lock bolt, said tumblers having interengaging features for rotatably adjusting one by the other, a separate knob mounted concentrically about the spindle knob, and arranged for adjusting the tumblers in a predetermined combination for releasing the lock bolt, an arm rigidly secured to the inner end of the spindle and engageable with the lock bolt for shifting the same, and a dished spring interposed between said arm and the last tumbler for yieldingly maintaining said tumblers in operable relation, said spring having a central portion of relatively small diameter for transmitting the pressure from one of the members between which it is interposed to the other, whereby to minimize the transmission of rotary movement from said arm to the tumblers, when the spindle is rotated.

3. In the construction defined in claim 1, a dished spring, convex in cross-section, interposed between the lock bolt actuating means on the spindle and the last tumbler, said spring being formed with a central portion of relatively small diameter for trans-

mitting the pressure from one of the members, between which it is interposed, to the other, for reducing the effective rotary motion transmitted by said means to the last tumbler.

- 5 4. In a permutation lock of the character described, the combination with a casing and a support to which it is secured, of a tumbler actuating knob journaled in the casing, 10 a graduated dial disposed concentric of and rotatable with said knob, a fixed index on the support with which the graduations of the dial are adapted to be registered, said knob and dial having interengaging features 15 for permitting angular adjustment relative to each other to a plurality of positions for varying the combination of the lock without altering the internal mechanism, and a plurality of tumblers having interengaging features 20 for adjusting one by the other, including a master tumbler having driving engagement with the knob, said master tumbler and knob having features adapted to connect them in any one of a plurality of angularly 25 related positions in the initial assembly of the parts; the knob and dial being provided with identification means for designating the relative position of said parts in the initial assembly of the lock.
- 30 5. In a permutation lock of the character described, the combination with a casing and a member on which it is mounted, of a rotatable tumbler actuating knob journaled in the casing and extending laterally therefrom, a graduated dial mounted concentrically of and rotatable with said knob, an escutcheon plate overlapping the periphery of the dial with means securing said plate to the casing with the mounting member 35 interposed, said plate being provided with a fixed index with which the graduations of the dial are adapted to be registered, said casing being provided with a member having an annular laterally projecting flange 40 concentric with the axis of rotation of the knob and arranged to co-operate with an offset in the escutcheon plate for maintaining a working clearance for the dial under said plate.
- 45 6. In a permutation lock of the character described, the combination with a casing and a member on which it is secured, of a tumbler actuating knob journaled in the casing, a graduated dial and index associated with the 50 knob, one of which is fixed with respect to the member and the other rotatable with said knob, said knob having a transverse flange disposed in the casing and having bearing contact with the inner wall of the casing for 55 limiting its outward movement, and a plurality of tumblers arranged co-axially with the knob including a master tumbler having driving engagement therewith, said tumblers having co-operating driving lugs for 60 adjusting one by the other, and the inner 65

face of said transverse flange of the knob being provided with a circumferential row of apertures one of which is adapted to be engaged by the driving lug of the master tumbler, said knob and master tumbler being adjustable relative to each other with the driving lug of said tumbler engaging in any one of said apertures in the flange for varying the combination of the lock.

7. In a permutation lock, the combination with a mounting member, of a casing secured to one side of said member, a rotatable tumbler-adjusting member projecting from said casing and extending through an aperture in the mounting member, a graduated dial disposed concentrically of and carried on said tumbler-adjusting member, and an escutcheon plate secured to the mounting member at the side opposite the casing, adapted to embrace the outer peripheral edge of the dial for confining it against axial movement, said escutcheon plate being provided with an index mark with which the graduations of the dial are adapted to be registered, said dial and tumbler-adjusting member having interengaging features adapted to permit detachable securing of the dial in a plurality of positions of angular adjustment on said tumbler-adjusting member, for varying the combination of the lock, said interengaging features being in the nature of a tongue-and-groove connection, one of the cooperating parts having a tongue adapted to be engaged with one of a plurality of grooves formed in the other cooperating part, said grooved part being provided with an identification feature to designate a certain groove with which the tongue on the other part is adapted to be engaged in the initial assembly of the lock.

8. In a permutation lock, the combination with a mounting member, of a casing secured to one side of said member, said casing being provided with an outwardly projecting cylindrical sleeve, a rotatable tumbler-adjusting member journaled in the sleeve and adapted to extend through the mounting member, a graduated dial mounted concentrically on said tumbler-adjusting member, said dial and tumbler-adjusting member having interengaging features adapted to permit detachable securing thereof in a plurality of positions of adjustment for varying the combination of the lock, and an index fixed with respect to said mounting member, with which element the graduations of the dial are adapted to be aligned for setting the combination of the lock.

9. In a permutation lock of the character described, the combination with a casing and a member on which it is secured, of a rotatable tumbler-adjusting member journaled in the casing and projecting outwardly therefrom, beyond the said member, a graduated dial disposed concentrically of the tumbler-adjusting member and rotatable therewith,

and an escutcheon plate secured to the mounting member and adapted to embrace the outer peripheral edge of said dial for holding the latter captive, said escutcheon plate being provided with an index mark with which the graduations of the dial are registered, said dial and tumbler adjusting member having mutually engaging features adapted to permit detachable securing of the dial in a plurality of positions of angular adjustment with respect to said tumbler adjusting member for varying the combination of the lock, said tumbler adjusting member being provided with an identification feature to indicate the relative positions of said dial and adjusting member in the initial assembly of the lock.
